P. KESSLER.

Alcohol Still.

No. 23,089.

Patented March 1, 1859.

UNITED STATES PATENT OFFICE.

PETER KESSLER, OF BELLEVILLE, ILLINOIS.

IMPROVEMENT IN APPARATUS FOR DISTILLING.

Specification forming part of Letters Patent No. 23,089, dated March 1, 1859.

To all whom it may concern:

Be it known that I, PETER KESSLER, of Belleville, in the county of St. Clair and State of Illinois, have invented certain new and useful Improvements in Distilling Apparatuses; and I do hereby declare the following to be a full, clear, and exact description of the same, reference being had to the annexed drawings, making a part of this specification, in which—

Figure 1 represents a front elevation of a distilling apparatus constructed according to my improvements. Fig. 2 is a vertical central section of my doubler, (the vessel which I use for rectifying the liquor.)

Similar letters of reference indicate corresponding parts in the two figures.

This invention consists in conducting the gaseous liquor from the still into a hollow cylindrical space which is partly filled up by a conical vessel filled with water, so that the impurities contained in the liquor are condensed by coming in contact with the cold sides of the water-vessel, and the pure liquor may be drawn off by a pipe leading to a suitable cooler, the water-vessels being so arranged in the space surrounding the same that the strength of the liquor may be determined by the quantity of water contained in said vessel, while at the same time the condensed impurities—*i. e.*, the low-wine—may be brought back to the first still by means of a faucet and without pumping.

To enable others skilled in the art to make and use my improved apparatus, I will proceed to describe it.

Two stills, A and B, are placed in such relation to each other as is usual in distilling apparatuses of this kind, the beer contained in the still A being heated by steam conducted to it by a pipe, C. The vapors thus arising from the beer ascend through a pipe, D, to the still B, from which they enter a vessel, E, by means of a pipe, F. This vessel is closed at the top by a cup, G, the bottom of which has an opening, *a*, and a plate, H, placed on the top of the cup G, has another opening, *b*, just opposite the opening *a*. Another cylindrical vessel, I, is placed on the

top of the vessel E, communicating with the same by means of the openings *a* and *b*, and the circulation is further increased by a hollow cylinder, J, attached to the top of the plate H, said cylinder having an open space, *c*, in its side, and being of such height as to reach to the bottom of a conical vessel, K, which fits into the cylindrical vessel I. The space L left between the outside of the vessel K and the inside of the vessel I is decreasing toward the top, and it runs out into a sharp point, as clearly represented in Fig. 2. The gaseous liquor contained in the vessel E ascends through the openings *a* and *b* and fills the space L, and if cold water is poured into the vessel K the impurities contained in the liquor are condensed. Water is admitted to the vessel K by means of a pipe, M, and a pipe, N, serves to carry off the surplus water, so as to prevent an overflowing. It is obvious that the condensation takes place more rapidly toward the top of the space L if the vessel K be filled with water up to the top, as the cold surface of the outside of the vessel K increases while the contents of the space L decrease, so that by putting more or less cold water into the vessel K the strength of the liquor may be regulated. The condensed impurities—*i. e.*, the low-wine—flow back to the vessel E through the openings *a* and *b*, and they are carried back to the still A by means of a faucet, O, which is attached to the vessel E close to its bottom. By this arrangement the pumping out of the low-wine is avoided, and a great deal of trouble and labor are saved thereby; and as a certain quantity of good spirits will always be contained in the low-wine, the flowing back into the still by this arrangement causes a great saving, as much of the liquor contained in the low-wine as treated in the usual way is lost, the low-wine being always pumped out in a high temperature, so that the liquor which escapes therefrom when coming in contact with the cold atmosphere is lost. The gaseous liquor, having thus been freed from its impurities to a degree which depends upon and may be regulated by the quantity and the temperature of the water contained in the vessel K,

escapes through a pipe, P, which leads into a suitable cooler, Q, from which it is drawn off into casks.

What I claim as my invention, and desire to secure by Letters Patent, is—

The employment of the stills A B and cooler Q, in combination with the vessels E I K, as described and shown, when said vessels

are arranged so as to have a tapering space, L, and an intermediate circulating passage, G a b J c, between them, substantially as and for the purposes herein set forth.

PETER KESSLER.
